[57] CLAIM

The ornamental design for a disposable syringe housing, as shown and described.

DESCRIPTION

FIG. 1 is a perspective view of a disposable syringe housing showing our new design;

FIG. 2 is a front elevational view thereof, the rear elevational view being identical thereto;

FIG. 3 is a side elevational view thereof, the opposite side elevational view being identical thereto;

FIG. 4 is a top plan view thereof;

FIG. 5 is a bottom plan view thereof;

FIG. 6 is a perspective view of an alternate embodiment of the disposal syringe housing;

FIG. 7 is a front elevational view thereof, the rear elevational view being identical thereto; and

FIG. 8 is a side elevational view thereof, the opposite side elevational view being identical thereto;

FIG. 9 is a top plan view thereof; and

FIG. 10 is a bottom plan view thereof.

FIG. 2
